UNITED STATES PATENT OFFICE.

SAMUEL W. BREWSTER AND LYMAN SHERWOOD, OF SOUTHEAST, NEW YORK;
SAID SHERWOOD ASSIGNOR TO SARAH E. SHERWOOD, OF SAME PLACE.

BOOT-DRIER.

SPECIFICATION forming part of Letters Patent No. 336,987, dated March 2, 1886.

Application filed January 4, 1886. Serial No. 187,617. (No model.)

To all whom it may concern:

Be it known that we, SAMUEL W. BREWSTER and LYMAN SHERWOOD, citizens of the United States, and residents of Southeast, in 5 the county of Putnam and State of New York, have jointly invented certain new and useful Improvements in Boot - Driers, of which the following is a specification.

Our invention has relation to means or apparatus specially designed for drying boots and other articles for foot-wear.

The object of our invention is to produce a simple, cheap, compact, durable, and efficient device wherein boots or shoes, either of leather or india-rubber, may be quickly and thoroughly dried both inside and outside without danger of damaging the articles by excessive heat, in which device the heat may be regulated to the desired degree and the consumption of fuel 20 economized. To accomplish this our improvements involve certain and useful peculiarities of construction and relative arrangements or combinations of parts, all of which will be herein first fully described, and then pointed 25 out in the claims.

In the accompanying drawings, forming part of this specification, Figure 1 is a sectional elevation of an apparatus constructed and arranged for operation in accordance with our 30 invention. Fig. 2 is a sectional elevation upon a plane passing through line $\alpha\alpha$ of Fig. 1. Fig. 3 is a plan view of the apparatus, showing the hinged door opened for the insertion of the boots or shoes to be dried. Fig. 4 is a 35 plan of a fragment showing the hinged door in closed position.

In all these figures like letters of reference wherever they occur indicate corresponding parts.

40 A is the main case or shell of the drier, which, with the hinged door, constitutes the receptacle for the boots or shoes to be dried. This is supported at a convenient height upon legs or standards, as B B, and is preferably 45 made of tin or sheet metal.

Within the shell A, and at a little distance from the lower margin thereof, are two plates, C and D, maintained at a slight distance from each other, as by rivets $a a$, and supported 50 within the shell by two straps, b b, preferably riveted to the shell, as at c c. These two

plates, C and D, are of smaller area than the horizontal section of the shell, and are held in place so as to leave free passage-way all around them for heat to enter the upper part of the 55 shell. The lower plate, D, against which the heat from the burners impinges, is preferably made of sheet-iron—such as Russia iron—so that it will well withstand the effects of direct heat, and it is slightly concaved along the 60 central line, as indicated in Fig. 2, whereby the distance between the two plates at this part is increased, thus insuring a more even distribution of heat to the upper plate, C, and avoiding overheating thereof. The upper 65 plate, C, may be made of lighter material—such as ordinary tin. The best effects are produced when the surfaces surrounding the boots or shoes are made of bright tin.

E is an oil-reservoir, having two ordinary 70 lamp-burners, of which the chimneys F F extend up within the lower open mouth of the case or shell. These burners should be adjusted under the concaved central part of the bottom plate, D, and under the straps b b. 75 The upper part of the shell is recessed, as at G G, to receive the legs of the boots or upper parts of the shoes, and the hinged lid or door H is correspondingly recessed, as at G' G', so that when the door is closed about the legs of 80 the boots or tops of the shoes the portions of these articles within the shell or case will be effectually inclosed.

The heel of the boot or shoe should rest upon one of the straps b and the ball of the sole upon the other, so that the article will be slightly 85 raised above the top plate, C.

Heat from the burners impinges against the bottom plate, D, and heated air and products of combustion enter the upper part of the case, 90 passing around the margins of the plates and through the space between the two plates, heating the interior of the shell and the articles therein thoroughly and uniformly.

By adjusting the flames of the lamp-burners 95 the degree of heat and the time required for drying may be regulated or controlled as desired. When in use, the apparatus may be employed also for illuminating purposes, as will be readily understood.

100 By extending the chimneys slightly above the lower margin of the case or shell, ordinary

drafts of air will not interfere with the heating effects. The lid or door H is hinged to the shell, as at h h, and drops down so as to open the end of the case or shell sufficient for 5 the ready and easy insertion or removal of the boots or shoes. The improved apparatus is specially well adapted for drying india-rubber boots, because of the accuracy with which the heat may be regulated so as not to burn them.

10 c In this class of articles the evaporation must take place from the interior, and being surrounded on all parts with uniform heat, the evaporated moisture passes freely out through the open tops of the boots, and all parts are 15 thus thoroughly dried.

In the case of leather boots and shoes which become saturated throughout, evaporation takes place internally as well as externally. The moisture from the interior passes out 20 through the open tops, and from the exterior gradually condenses and passes out of the shell through the openings around the double bottom plates.

The improved apparatus, constructed and 25 arranged substantially as above explained, will be found to admirably answer the purpose or object of the invention as previously set forth, the heat being entirely utilized to best advan-

tage for producing the drying effects, and the consumption of fuel being therefore only such 30 as necessary to accomplish the required work.

Having now fully described our invention, what we claim as new herein, and desire to secure by Letters Patent, is—

1. In an apparatus for drying boots, the 35 combination, with the shell or casing having the double bottom and the recessed upper portion, of the hinged lid or door correspondingly recessed, substantially as and for the purposes set forth.

2. The herein-described apparatus for drying boots, composed of the shell or casing having the hinged door or lid, the two plates secured within the shell, the legs or standards, and the oil - reservoir with the burners and 40 chimneys, all arranged and combined for operation substantially as shown and described.

Signed at Brewster, in the county of Putnam and State of New York, this 2d day of January, A. D. 1886.

SAMUEL W. BREWSTER.
LYMAN SHERWOOD.
